JALOUSIE WINDOWS

Thomas J. Metzger, North Miami, Fla., assignor to
Lu Vent Corporation

Application April 19, 1954, Serial No. 424,002

4 Claims. (Cl. 20—62)

The present invention relates to window jalousies. More particularly, the present invention relates to window jalousies which consist of a knock-down frame, which may be easily assembled, and of a plurality of slats, made of, for example, glass or similar material which are pivotally supported in the frame in a manner to be actuated simultaneously by a single actuating mechanism for opening and closing thereof.

It is, accordingly, an object of the present invention to provide a jalousie window which may be easily assembled and installed by the user thereof.

It is another object of the present invention to provide a jalousie window which has superior characteristics as regards its method of manufacture and installation.

A still further object of the present invention resides in the provision of a frame for jalousie windows which consists of a plurality of individually manufactured parts, and which are made preferably by extrusion to provide an absolutely rigid frame.

It is a still further object of the present invention to provide a jalousie window which is composed of a plurality of prefabricated, individual elements, and which, by reason of the accuracy of the parts and the design involved, may be installed and assembled in a relatively short time.

It is a further object of the present invention to provide a jalousie window to which a screen or storm window may be readily attached.

It is still another object of the present invention to provide a jalousie window with effective seals between the various parts to prevent bugs and insects from entering therethrough.

In particular, it is an object of the present invention to provide a seal between the glass and frame with the windows closed in the form of a plastic strip between the glass and the frame.

It is a further object of the present invention to provide counter-balanced louvers which open easily, close tightly, and insure smooth and effortless operation.

It is a still further object of the present invention to provide glass holding clips which overlap each other so as to give a perfect weather-tight seal even if the glass pieces are short.

It is a still further object of the present invention to provide a special removable tension spring between the glass and the clips to prevent rattling, and to hold the glass securely in place, thereby effecting a weather-tight seal between the various parts.

It is still another object of the present invention to provide a spring which is removably mounted on the clips so as to permit ready exchange of the spring in case of fatigue thereof, thereby assuring at all times proper tension of the spring and therewith proper seal of the clip with the window frame.

It is a still further object of the present invention to provide a jalousie window frame having a plaster lock feature to greatly speed up the finishing around the frame after installation.

2

Another object of the present invention is to provide a jalousie window which requires no bolting during assembly, which is designed for long, convenient and trouble-free service and which offers a rigid and durable frame.

These and other objects and advantages of the present invention will become more obvious from the following description when taken in connection with the accompanying drawing which shows for purposes of illustration only one preferred embodiment, and wherein:

Figure 1 is a front view of the jalousie window in accordance with the present invention as viewed from the inside of the window.

Figure 2 is a cross sectional view taken along lines 2—2 of Figure 1.

Figure 3 is a front view of the jalousie window in accordance with the present invention as viewed from the outside of the window.

Figure 4 is a cross sectional view taken along lines 4—4 of Figure 1.

Figure 5 is a cross sectional view on a larger scale, showing in greater detail some of the features of Figure 4, including the mounting of the screen.

Figure 6 is an enlarged cross sectional view similar to Figure 2, with parts thereof broken away to show the actuating mechanism of the window.

Figure 7 is a cross sectional view taken along lines 7—7 of Figure 6.

Figure 8 is a cross sectional view along lines 8—8 of Figure 6.

Figure 9 is an exploded perspective view of the jalousie window frame with the various parts thereof shown in the positions just prior to assembly, and

Figure 10 is a perspective enlarged view of the clip and removable spring in accordance with the present invention.

Referring now to the drawing, wherein like reference numerals are used throughout the various views to designate like parts, and more particularly to Figure 9 thereof, reference numeral 21 designates the head or top frame member. The base member 22 is substantially parallel to top member 21 and spaced therefrom by two substantially parallel side members 23 and 24 so as to form a rectangle or a square, as the case may be.

The top member 21 consists of a substantially flat main surface 25 and two end members 26 and 27 extending at right angle thereto over substantially the entire length of the top member 21.

A somewhat shorter lip member 28 projects toward the inside of the window from the end member 27 at an angle, such as, for example, 45 degrees. The flat surface 25 is provided with slots 29 and 29', and 30 and 30' at right angles with each other so as to provide an increased rigidity of the frame, and are substantially distributed over the four corners of the surface 5 so as to engage with appropriately arranged corresponding fingers of the side members 23 and 24 as will be more fully described hereinafter.

The lip member 28 serves the purpose of providing an effective seal with the windows or louvers in the closed position. In order to facilitate assembly of the top member 21 with side members 23 and 24 the lip member 28 is somewhat shorter than the top member at both ends thereof so as to provide cut-out portions 31.

Of course, the main flat surface 25, end members 26 and 27 and lip member 28 are integral with each other, and may be made from one piece of material by appropriately extruding and cutting the material.

The side members 23 and 24 are of substantially similar design, and are mirror images of each other. Side member 23 is provided with a main flat surface 32 and a flange

member 33 which extends inwardly at right angle thereto on the side thereof nearer the inside of the window.

The flange member 33 extends inwardly at a slight distance from the end of the main flat surface 32, as clearly shown in Figure 9 of the drawing.

The flange member 33 is provided with an upwardly extending finger 34 and a downwardly extending finger 35 for engagement with slots 30 and 51 of the top and base frame members respectively. Adjacent the main flat surface 32 is a channel-shaped surface 36 which is displaced inwardly of and parallel with the main flat surface 32 by the connecting portions 39 and 40, which are disposed at substantially right angles with respect to the substantially parallel surfaces 32 and 36. The channel shaped portion 36 is provided with an upwardly extending finger 37 and a downwardly extending finger 38 which engage slots 29 and 50 of the top and base frame members, respectively.

The connecting portion 40 is provided with a small overlapping portion 41 as best shown in Figures 5 and 8. The channel member 36 also comprises a downwardly lengthened portion 42 which is complementary with the step 48 of the base frame member as will be more fully explained hereinafter.

The other side member 24, which is a mirror image of the side member 23, has correspondingly similar parts designated with primed reference numerals, and is, therefore, not described in detail. However, it is noted that the side member 24 includes a cut-out portion or slot 43 for purposes of accommodating the actuating mechanism for the louver windows or slats.

The base frame member 22 includes a main flat surface 44, an upwardly extending end member 45 slightly shorter than the main flat surface 44, as clearly shown in Figure 9, and a step-like portion of substantially equal length as the main flat surface 44 and of width substantially equal to the width of the lengthened portion 42 of the channel member 46. The step-like portion is formed by a substantially horizontal part 48, which is substantially parallel to the main flat surface 44, a downwardly extending intermediate connecting part 47, and end member 49 opposite connecting part 47 which also extends downwardly substantially parallel to the member 47. The main frame surface 44 of the base frame member is provided with slots 50 and 51 and slots 50' and 51' for engagement with the fingers 35 and 38, and fingers 35' and 38' of the side members 23 and 24, respectively. It is noted that the slots 50 and 50' are placed at right angles with the slots 51 and 51' to provide greater rigidity of the frame.

The individual parts of the frame, illustrated in Figure 9, are assembled by simply extending the fingers 34, 34', 37, 37', 35, 35', 38 and 38' into slots 30, 29, 30', 29', 51, 50, 51' and 50' respectively, whereupon the ends of these fingers protruding therefrom are bent or flattened in parallel with the base and top frame members 22 and 21 so as to secure the frame together. It is only necessary during the assembly of the frame to maintain a substantial perpendicular relationship of the various members, which may be readily accomplished with the simplest of tools.

The actuating housing 51 for the window actuating mechanism, best shown in Figures 2 and 6, is attached to the flange part 33' of side member 24 by means of flanges 62 and 62', and is secured to the flange part 33' in any conventional manner, as by means of screws 63 and 63'. A helical worm gear 64 is housed within the housing 61 and has an axis substantially parallel to the laterally protruding sleeve 65 of the housing 61, best shown in Figures 2 and 4.

The helical worm gear 64 is suitably journaled in the laterally protruding sleeve 65, and may also be journaled in the housing 61 in any appropriate manner, including bearings of any suitable type. The laterally protruding sleeve 65 may assume any angle, and is shown in the drawing in Figure 8 as assuming an angle of substantially 45°.

The helical worm gear 64 includes a shaft (not shown) which extends outwardly of sleeve 65 and which may be provided with splined surfaces (not shown) over which the hollow end of the actuating handle 66 is slipped. The actuating handle 66 is fastened to the splined shaft of worm gear 64 by means of a set screw 67 (Figure 8), so as to rotate the worm gear with rotation of the handle 66.

The helical worm gear 64 meshes with a segmental pinion gear 68 which is pivotally supported in housing 61 by a transverse shaft 69 which is suitably journaled therein. The pinion gear 68 is provided with an arm 70 extending outwardly through the opening 43 in the flange portion 33 of side member 24 and is pivotally connected with a link 71 by a pivotal connection 72, which may be of any suitable type, such as a rivet, etc.

A plurality of window supporting clips 73, 74, 75 and 76 are shown in Figure 2, which are identical, and of which only one is shown in greater detail in the perspective view of Figure 10. It is understood that any number, suitable for the particular size of the window, of these clips may be provided depending only on the number of louvers or slats desired with each window.

Each supporting clip 73, 74, 75 and 76 comprises a main lateral flat surface 77 which is somewhat elliptical in shape, and which is provided with bores 78 and 79 for purposes to be more fully described hereinafter. The main flat surface is also provided with punched-out semi-circular holes 80 and 80', with the punched-out portions 81 and 81' of the flat surface 77 corresponding to holes 80 and 80' remaining securely fastened to surface 77 at one side thereof and extending inwardly at right angle with respect to the main surface 77. Each clip also comprises a front retaining ledge 82 for the slat, a bottom retaining ledge 83 and a top projection 84 which may be bent parallel to the bottom ledge 83 after the window is inserted. The window is retained on 5 sides thereof by the surfaces of members 77, 81 and 81', 82, 83 and 84.

Each clip is pivotally supported in the side members 23 and 24, and more particularly in the channel-shaped members 36 and 36' thereof by a pivotal support 85, which may be of any suitable type, such as a rivet.

In order to obtain simultaneous movement of all the louvers or slats with operation of handle 66, a common actuating rod 86 is provided which is pivotally connected with each clip by means of a pivotal connection 87, of any suitable type, such as a rivet or the like. Preferably, however, the clip, which is also connected with the link 71, is provided with a screw 88 providing the pivotal connection which threadably engages the link 71 and which is freely rotatable in the common actuating rod 86 as well as in the bore 78 of the clip 74.

Reference numeral 89 designates the glass louvers or slats which may be of any suitable material, such as transparent or opaque glass, and which are securely held in position by the surfaces 77, 81 and 81', 82, 83 and 84 of each of the clips 73, 74, 75 and 76 respectively.

In order to provide for proper sealing between the clips 73, 74, 75 and 76 and the window louvers or slats 89, metallic springs 90 are inserted therebetween, which are best illustrated in Figure 10.

Each metallic spring 90 consists of a substantially flat middle section 91 which engages the glass and which is provided with a cut-out portion 92 in the center thereof extending in the longitudinal direction of the flat section 91 as slots 93 and 93', which are so dimensioned as to engage with the punched-out portions 81 and 81' of the main flat surface 77 of the clips.

Each spring 90 further comprises bent end portions 94 and 94' which provide for resilient engagement with the main flat surface 77 of the clip.

The spring 90 is inserted intermediate the clips and the slats in such a way that the slots 93 and 93' receive the members 81 and 81', while the middle section 91 of the spring 90 engages with the window or slat whereas the

end members 94 and 94' provide for engagement with the clip 77, whereby the resiliency of the material, from which the spring member 90 is made, assures that no rattling occurs between the slats and the clips, even during stormy or gusty weather.

It is also noted that the clips provide an effective sealing for the louver windows, since the external flat surfaces of clips 73, 74, 75 and 76 are firmly pressed against the inside of the channel shaped members 36 and 36' at all times.

The readily interchangeable feature of the springs 90, which may be simply lifted out of their engagement with the clips 73, 74, 75 and 76 after removal of the individual slats, constitutes an important feature, since the springs 90 may be readily replaced if they lose their resiliency by wear and tear thereof or due to fatigue of the material.

The use of the middle section 91 for engagement with the ends of the glass louvers or slats provides for a substantial contact surface, and thereby insures proper action of the spring.

If desired, the frame in accordance with the present invention may be readily adapted for use with a screen 101 which may be of any suitable material such as mesh or plastic, and which is contained in a screen frame 102. (See Figure 1.) Screen retaining clips 103 are suitably fastened to the flange members 33 and 33', and retain the screen in assembled position relative to the louver window structure.

In the operation of the assembled louver window jalousie it is only necessary to operate the handle 66 which through worm gear 64, pin 68, arm 70, link 71 and common actuating rod or link 86 opens or closes simultaneously all the slats or louvers of the jalousie.

The foregoing description of the jalousie window in accordance with the present invention also shows clearly that the structure lends itself readily for manufacture of the individual parts by the extrusion process of light metals, such as aluminum, and may be assembled in a simple manner without special skill or tools.

While I have shown and described one preferred embodiment in accordance with the present invention, it is understood that the same is not limited thereto, but is susceptible of various changes and modifications as known to a person skilled in the art, and I intend to cover all such changes and modifications except as defined by the appended claims.

I claim:

1. Jalousie window comprising a frame, a plurality of window louvers, clip means for retaining said louvers in assembled position in said jalousie, means for pivotally

mounting said clip means on said frame, removable spring means interposed between said clip means and said louvers urging said clip means against said frame, and common actuating means for all of said clip means, said clip means including protruding members extending in a direction essentially parallel to said pivotal mounting means and said spring means being provided with slots for engagement with said protruding members.

2. Jalousie window according to claim 1, wherein said 10 spring means comprises end portions for engagement with said clip means and a center portion for engagement with said louvers.

3. Jalousie window comprising a frame, a plurality of 15 window louvers, clip means with a base portion located on both ends of each louver for retaining the same in assembled position in said jalousie, means for pivotally mounting each clip means on said frame, a removable spring with a substantially flat center portion for engagement with a corresponding window louver and with 20 spring fingers on both ends thereof for engagement with a corresponding clip means interposed between a respective clip means and louver to urge said clip means against said frame in weather-tight relationship, each clip means being provided with punched-out portions extending substantially at right angle to the base portion 25 thereof for engagement with corresponding slots provided in the center portion of said springs.

4. A jalousie window comprising a frame, a plurality 30 of window louvers, clip means for retaining said louvers in assembled position in said jalousie, means for pivotally mounting said clip means, removable spring means interposed between said clip means and said louvers to urge said clippings against said frame, and common actuating means being provided with complementary engaging 35 means located on the side of said clip means adjacent said louvers for removably securing said spring means on said clip means, said engaging means including projecting members simultaneously serving as retaining surfaces for a corresponding window louver on one of the two parts 40 consisting of said spring means and clip means, and the other of said parts being provided with corresponding slots.
